UNITED STATES PATENT OFFICE.

ANGUS F. HANNEY, OF CHICAGO, ILLINOIS.

LAUNDRY APPLIANCE.

Application filed August 2, 1920. Serial No. 400,849.

To all whom it may concern:

Be it known that I, ANGUS F. HANNEY, a citizen of the United States, and a resident of the city of Chicago, county of Cook, and 5 State of Illinois, have invented certain new and useful Improvements in Laundry Appliances, of which the following is a specification.

My invention relates to new and useful 10 improvements in laundry appliances and more particularly to appliances for handling laundry markers, the object of the invention being to provide a simple and efficient arrangement for the purpose, by 15 means of which the handling of markers for laundry purposes is greatly facilitated.

Other objects will appear hereinafter.

The invention consists in the combination and arrangements of parts hereinafter 20 described and claimed.

The invention will be best understood by reference to the accompanying drawings forming a part of this specification, and in which,

25 Fig. 1 is a side elevation of a laundry marker holder employed in the appliance,

Fig. 2, is an end view of the same,

Fig. 3, a section taken on line 3—3 of said 30 Fig. 1,

Fig. 4, a section taken on line 4—4 of said Fig. 1,

Fig. 5, a side view of a carrier employed 35 in the appliance shown in position of use,

Fig. 6, a detailed side view of one of a plurality of laundry markers employed in the appliance and in open position,

Fig. 7, a view similar to Fig. 6, but showing the markers in a closed position, and

40 Fig. 8 is a fragmentary sectional detail view taken substantially on line 8—8 of Fig. 1.

The preferred form of construction as illustrated in the drawings comprises a laundry marker holder having end plates 8 connected by three rods or bars 9, said rods or bars 9 being arranged to support a plurality of laundry markers 10 as indicated. Each of the markers 10 is provided with a pin point 11 and a co-operating lock 12 pivoted thereon. Each marker is also provided with 45 a slot or perforation 13 and a suitable trig-

ger 14 traversing one end of said slot and adapted and arranged to lock the locking member 12 in locking position as indicated in Fig. 7. The specific form of the marker 55 10 constitutes the subject matter of a separate application bearing Serial No. 400,850 filed on even date herewith and is there fully described and illustrated, the only feature 60 of said marker which is material here being the slot 13.

A wire bail 15 has its ends 16 pivotally mounted in the end plates 8 and is adapted and arranged to be swung over the upper edges of the markers 10 to hold the same 65 in place on the supporting bars 9, a tension spring 17 being connected with said bail and arranged and adapted to hold the same in such engagement. The bail 15 is angularly 70 formed as indicated, and the spring 17 connected therewith by means of an eye 17' resting in the angle of said bail but sliding freely thereon and whereby said spring normally holds said bail in either its operative or inoperative positions.

I also provide a carrier 18 in the form of a bar adapted to pass through the slots 13 in the markers 10, said carrier being removably supported on a suitable bracket 19. The carrier 18 also constitutes part of the 80 said separate application and is fully illustrated and described therein, it being sufficient to state here that said carrier is such that the markers 10 slide freely thereon and are adapted and arranged to release 85 the laundry articles 20 during such sliding.

I also provide a clamping plate 21, substantially in U form as indicated, and sliding freely upon the rods 9. The clamping plate 21 carries a clamping lever 22 pivotally mounted thereon and normally pressed by a coiled spring 23 to clamping engagement with the lowermost of the rods 9 and whereby said clamping plate 21 may be readily adjusted along the rods 9 and secured in adjusted positions. The end plates 8 are provided with registering notches 24 and the clamping plate 21 is provided with a corresponding registering notch 25 adapted to receive the carrier bar 18 when the markers 100 are in position on the rods 9.

In operation the markers are assembled

2

on the carrier bar 18 as indicated in full lines in Fig. 5. The carrier bar 18 is then detached from the bracket 19 and with the markers 10 thereon inserted in the holder 5 between the end plates 8 and resting upon the rods 9. Clamping plate 21 is then adjusted into clamping engagement with said markers as indicated in Fig. 1 and the bail 15 adjusted into holding engagement with 10 the upper edges of said markers, as indicated. Then the carrier bar 18 is removed by sliding the same longitudinally through the notches 24 and 25 and the slots 13 in said markers. The markers will thus be held in 15 the same order and arrangement in which they were placed on the bar 18 until desired for further use. The markers are stamped on the lips 26 with an identifying mark to identify a particular customer and 20 thus the markers for that customer may be readily retained and preserved for re-use on the work from laundry of that particular customer, thus greatly facilitating the operation of the laundry.

25 While I have illustrated and described the preferred form of construction for carrying my invention into effect, this is capable of variation and modification without departing from the spirit of the invention. 30 I, therefore, do not wish to be limited to the precise details of construction set forth, but desire to avail myself of such variations and modifications as come within the scope of the appended claims.

35 Having described my invention, what I claim as new and desire to secure by Letters Patent is:—

1. A device of the class described comprising a holder adapted and arranged to receive markers; means for detachably holding said markers in said holder in the order received; means for preventing the removal of said markers from said holder; and means for holding said holding means in its operative position when said markers are being received or removed from said holder.

40 2. A holder of the class described comprising similar end plates and bars connecting said plates together, said bars being arranged and adapted to receive and support a number of laundry markers from a marker carrier.

45 3. A device of the class described comprising a holder adapted and arranged to receive markers from a carrier, means for detachably holding said markers in said holder; means for holding said holding means in its inoperative position while said markers are being transferred from said carrier to said holder, and means adapted to be adjusted into clamping engagement with said markers, to hold said markers in the order received.

50 4. A device of the class described comprising a holder adapted and arranged to re-

ceive markers; means for detachably holding said markers in said holder and slidably mounted means adapted and arranged to be adjusted into clamping engagement with said markers for holding said markers in said holder in the order received.

5. A laundry marker holder comprising supporting bars adapted and arranged to support a plurality of removable markers and a U-shaped clamping plate mounted to slide on said bars and adapted to be adjusted into clamping engagement with said markers.

6. A laundry marker holder comprising a support adapted and arranged to support a plurality of markers therein; and pivotally mounted means for detachably securing said markers in said holder and a spring member associated with said securing means for holding said means in its operative or inoperative position.

7. A laundry marker holder comprising two similar end plates; three bars connecting said end plates; a spring held clamp slideable on said bars; and means for detachably holding markers in engagement with said bars.

8. A laundry marker holder comprising two similar end plates; three bars connecting said end plates, a clamp slideable on said bars; means for detachably holding markers in engagement with said bars comprising a wire bail pivotally connected with said end plates and adapted and arranged to engage the edges of markers supported on said bars; and a spring holding said bail in operative engagement with said markers.

9. A device of the class described including a marker carrier, and a marker holder adapted and arranged to receive markers from said carrier.

10. A device of the class described including a marker carrier, a marker holder adapted and arranged to receive markers from said carrier and hold said markers in the same order as carried by said carrier upon removing said markers simultaneously from said carrier.

11. A laundry marker holder comprising end plates and bars connecting said plates together, said bars being adapted to support a number of markers received from a carrier; and a member carried by said end plates adapted for engagement with said markers for releasably holding said markers on said supports upon removal from said carrier.

12. A laundry marker holder comprising similar end plates; bars connecting said end plates and arranged and adapted to receive and support a plurality of markers from a carrier; a clamping member mounted on said bars adapted to be brought into engagement with said markers; a wire member carried by said plates adapted for en-

gagement with said markers for holding said markers in engagement with said bars upon removal of said markers from said carrier; and a spring member carried by ⁵ one of said plates and connected to said wire member for holding said member in either its operative or inoperative position.

In testimony whereof I have signed my name to this specification in the presence of two subscribing witnesses.

ANGUS F. HANNEY.
